US00D588866S

(12) **United States Design Patent**
Ho

(10) **Patent No.:** **US D588,866 S**
(45) **Date of Patent:** **** Mar. 24, 2009**

(54) **HEATING COVER WITH VAPOR RIM**

(75) Inventor: **Joseph Chor Ho**, Thornhill (CA)

(73) Assignee: **Founder Plastics, Inc.**, Toronto, Ontario (CA)

(**) Term: **14 Years**

(21) Appl. No.: **29/317,172**

(22) Filed: **Apr. 23, 2008**

(30) **Foreign Application Priority Data**

Oct. 23, 2007 (CA) 122844

(51) **LOC (9) Cl.** **07-02**

(52) **U.S. Cl.** **D7/391**

(58) **Field of Classification Search** D7/317-319, D7/354, 391-392.1, 392, 396.2, 505, 510-511, D7/540-542, 610, 629; D9/429, 435, 440, D9/443-444, 447-454, 503-504; 99/645; 165/47; 215/200, 211, 224, 243, 252; 220/293, 220/367.1, 523, 700-703, 711, 713-715, 220/719, 780

See application file for complete search history.
